ATTORNEY

UNITED STATES PATENT OFFICE.

ALEXANDER B. HEADLEY, OF RAHWAY, NEW JERSEY, ASSIGNOR TO THE LOEWENBERG COMPANY, OF NEWARK, NEW JERSEY, A CORPORATION OF NEW JERSEY.

GOLF-BAG.

1,119,508.

Specification of Letters Patent. Patented Dec. 1, 1914.

Application filed July 27, 1912. Serial No. 711,776.

To all whom it may concern:

Be it known that I, ALEXANDER B. HEADLEY, a citizen of the United States, residing at Rahway, in the county of Union and State of New Jersey, have invented certain new and useful Improvements in Golf-Bags; and I do hereby declare the following to be a full, clear, and exact description of the invention, such as will enable others skilled in the art to which it appertains to make and use the same, reference being had to the accompanying drawing, and to figures of reference marked thereon, which form a part of this specification.

This invention relates to a closure for the open end of a golf-bag, consisting of an extension of substantially tubular form which is provided with means on its end for closing it and also locking it. The extension is preferably secured to the bag in a manner that permits of its being detached from the bag, but the fastening means employed may be adapted to lock the extension to the bag. The extension is preferably made with an open end which is provided with means for closing it and locking it in its closed position. The extension is adapted to cover and thus protect the sticks carried in the bag.

The invention is illustrated in the accompanying drawing, in which—

Figure 1 is a side view of a golf-bag with the extension folded inward so that it is not in view. Fig. 2 is a section of the bag with the extension projected from the bag. Fig. 3 is a perspective view of the extension, and Fig. 4 is a section through one of the fastening mediums.

In the drawing I illustrate a golf-bag 10 of any usual style, having the conventional grip and shoulder-strap. The bag is provided with an extension 11 which fits the bag 10, being substantially tubular in form and having a flap 12 extending from one end. The bag is provided at its top edge with slits 13 which are made with reinforced edges. The extension is provided near its bottom edge with staples 14 attached in any suitable manner. The preferred way of attaching the staples is to make them with back strands 15 passing behind leather or similar strips 16 so that the staples are pivoted to the extension. The staples 14, when

passed through the slits 13, are held in place by a suitable binding strand 17, which is usually a strap with a buckle or lock, to prevent its accidental removal. When the extension is fastened to the end of the bag it can be folded inward, as shown in dotted lines in Fig. 1, or it can be extended from the end of the bag as shown in Fig. 2. The extension when extended protects the ends of the clubs and sticks in the bag, and to do this it is provided with closing means. The extension is closed by having the flap 12 fold over the opposite side 18 of the open end of the bag, (see Fig. 2). Said opposite side has staples 19 secured thereto and the flap 12 has slits 20 to receive the staples. A staple 21 can be fastened to the rear of the flap to assist in holding the strap 22 which passes through the staples when they project through the slits to lock the flap in its closed position. The strap 22 is carried around the bag when it is not used to close the extension, as will be seen from Fig. 1. The strap 22 has a suitable lock or bolt.

The extension is easily and quickly put in place or removed, and provides a cheap and positive means for closing the end of a golf-bag. When folded inward the extension is out of the way and does not interfere in any way with the use of the bag.

Having thus described my invention, what I claim is:—

1. The combination of a golf-bag, with an extension fitting the end of the bag, means for securing the extension to the top of the bag, the extension being substantially cylindrical and having open ends, one open end having a flap on one side to fold over the opposite side, and detachable fastening means encircling the extension near its top edge and disposed to also embrace the end of the flap when it is folded over for securing the flap in its folded position, the extension when open being adapted to be folded within the bag and lie against the sides thereof.

2. A closure for a golf-bag comprising a substantially cylindrical extension of flexible material having means at its bottom for securing it to the top of a golf-bag, a flap extending at one side from the top of the extension and having slits near its end, staples

on the edge of the extension opposite the flap
and placed so that they extend through the
slits when the flap is folded over, staples on
the extension at the base of the flap, and a
5 strap passing through the staples to lock the
flap in closed position and to compress the
bag and flap when closed.

In testimony, that I claim the foregoing,
I have hereunto set my hand this 19th day of
July, 1912.

ALEXANDER B. HEADLEY.
